SWIMMING POOL

Henry Fischler, Bayside, N.Y., assignor to International Swimming Pool Corporation, Roslyn Heights, N.Y., a corporation of New York

Filed Apr. 8, 1963, Ser. No. 74,335

Term of patent 7 years

(Cl. D13—1)

FIG. 3

FIG. 1 is a perspective view of the swimming pool, showing my new design.

FIG. 2 is a top plan view of the swimming pool, and FIG. 3 is a side elevational view of the swimming pool. I claim:

The ornamental design for a swimming pool, as shown.
